V. R. BOTTONE.

LOCK.

APPLICATION FILED MAR. 30, 1921.

1,384,590.

Patented July 12, 1921.

Victor R. Bottone

By *Dellitt Goodwin*

Attorney

UNITED STATES PATENT OFFICE.

VICTOR R. BOTTONE, OF PHILADELPHIA, PENNSYLVANIA, ASSIGNOR OF ONE-HALF
TO JOHN S. McALEER, OF PHILADELPHIA, PENNSYLVANIA.

LOCK.

1,384,590. Specification of Letters Patent. Patented July 12, 1921.

Application filed March 30, 1921; Serial No. 456,844.

To all whom it may concern:

Be it known that I, VICTOR R. BOTTONE, a subject of Great Britain, residing at Philadelphia, in the county of Philadelphia and State of Pennsylvania, have invented certain new and useful Improvements in Locks, of which the following is a specification.

My invention relates to improvements in a lock or shackle adapted for use upon various articles to prevent theft, and which is particularly adapted for use in connection with an automobile, for locking the control levers in a position to prevent the starting of the automobile, also for locking one or two spare tires upon the tire carrier or for locking a wheel with the steering knuckle or rods.

The object of my invention is to provide a lock having a body member and a cross-bar adjustable to various positions upon the body member; a further object of invention is to provide means for rigidly locking the crossbar securely upon the body member comprising a key controlled device; a still further object of my invention is to construct the lock in such a manner that it may be made of very heavy metal of sufficient size to insure against its being cut with any portable metal shearing device.

Referring to the accompanying drawing; Figure 1, is a side elevation of my improved lock; Fig. 2, is an end view of Fig. 1, Fig. 3 is a plain view of the cross bar, shown in Fig. 1, detached; Fig. 4, is a horizontal section, on line 3—3 Fig. 2; Fig. 5 is a vertical section on line 5—5 Fig. 4, and Fig. 6, is a perspective view of a portion of the locking rod.

In the accompanying drawing in which like reference characters refer to like parts, 1 represents the body member of the lock, which is made of very heavy metal, preferably of round bar stock, and formed into a U-shaped member having parallel side members 2 and 3. Said side members are each provided with a series of recesses 5 alining with each other.

A cross-bar or member 7 is adapted to be placed and secured upon the side members of the body portion. Said cross-bar 7 is provided with lugs 8 and 9, having apertures 10 and 12 formed through the same, through which the side members 2 and 3 of the body member may enter the lugs.

A locking-rod 14 is rotatably mounted in

the cross-bar 7 and is of sufficient length to extend transversely through the apertures 10 and 12, formed in the lugs 8 and 9, and occupy the said recesses 5, formed in the side members 2 and 3, when the cross bar 7 is placed upon the body portion, as shown in Figs. 4 and 5. The center line of the rod 14 is positioned approximately upon the line of the periphery of the apertures formed in the lugs 8 and 9.

The rod 14 is provided with transverse recesses 15 and 16 formed in the side surface of the said rod. Said recesses are of sufficient dimensions to allow the side members 2 and 3 to slide through the apertures 10 and 12 in the lugs 8 and 9, when the rod 14 is turned into the position shown in Fig. 3, with the recesses 15 and 16 in the rod registering with the recesses 10 and 12 in the lugs 8 and 9.

The rod 14 is provided at one end with a flat tongue 18 which is engaged by the barrel-lock 20, which is secured in the end of the cross-bar 7 and is controlled by a key 21 for securing the rod in a fixed position and for turning it to engage or disengage the body member.

My improved lock or shackle may be readily placed around an object to be secured against theft, and the cross-bar may be adjusted upon the body member to suit objects of different sizes and the cross-bar may be readily attached and detached by the key controlled device.

My device is simple in construction permitting it to be made of very heavy material which cannot readily be destroyed. The lock is made so that it will embrace many different sized objects, thus avoiding the use of chains which may be readily cut with hand tools.

Having thus described my invention, I claim and desire to secure by Letters Patent:

1. A device of the character described comprising a body member, a bar having a portion adapted to embrace the body member; a locking member mounted in the bar adapted to be moved into and out of the engaging position with the body member, and said body member having a series of recesses formed therein to receive the locking member and hold the said bar at various positions upon the body member.

2. A device of the character described comprising, a member having a transverse

recess formed in the side thereof, a receiving member having an aperture formed therein adapted to receive the first mentioned member, a locking rod rotatably mounted in the said receiving member, said locking-rod having a transverse recess formed in the side thereof adapted to align with the said aperture formed in the said receiving member and means for rotating the locking-rod so that it will engage the first mentioned member by occupying the transverse recess formed in the first mentioned member.

3. A device of the character described comprising, a U-shaped body member, a cross-bar having apertures formed through the same for the passage of the side portions of the body member, a locking member mounted within the cross-bar adapted to simultaneously engage the said side portions of the body member, and means for moving

the locking member into and out of engagement with the body member.

4. A device of the character described comprising, a U-shaped body member, a cross-bar having apertures formed through the same for the passage of the ends of the body member, a locking-rod mounted within the cross-bar and extending transversely through the said recesses formed in the cross-bar to receive the body member, said body member having a series of transverse recesses formed therein adapted to be occupied by the said locking rod for securing the cross-bar upon the body member, said locking rod having recesses formed in the side thereof for the free passage of the body member when the locking-rod is in the disengaging position, and key controlled means for rotating the locking-rod.
